CLAIM

The ornamental design for an assembling toy block as shown and described.

DESCRIPTION

FIG. 1 is a perspective top plan view of an assembling toy block;

FIG. 2 is a perspective bottom plan view thereof;

FIG. 3 is a top plan view thereof;

FIG. 4 is a front view thereof;

FIG. 5 is a bottom plan view thereof;

FIG. 6 is a reference top plan view thereof;

FIG. 7 is a section view taken along line 7-7 of FIG. 6;

FIG. 8 is an environmental section view taken along line 8-8 of FIG. 10;

FIG. 9 is an environmental perspective view showing the assembling toy block in use; and,

FIG. 10 is an environmental perspective view showing the assembling toy block in another state of use.

The broken lines represent the environment in which the article resides and forms no part of the claimed design.
